STOKER CONTROL SYSTEM

Virgil Robins Tate, Milwaukee, Wis., assignor to
 Perfex Corporation, Milwaukee, Wis., a corpora-
 tion of Wisconsin

Application October 13, 1939, Serial No. 299,240

27 Claims. (Cl. 110—101)

This invention relates in general to control systems and more particularly to stoker control systems.

In stoker control systems it is customary to provide some automatic means which, in case of failure of the fire in the stoker retort, will shut the stoker down until manually reset. This means is generally referred to as an outfire control and usually consists of a thermal actuated device and a switch. This thermal device is usually mounted in the stack of a stoker-fired furnace and is arranged to open the switch in the event that the stack temperature falls to too low a value, indicating that the fire has been extinguished or has been very nearly extinguished. This switch is usually connected in series with the stoker motor in order that the stoker cannot operate with the switch open.

Thermal operated devices of this class have been unsatisfactory in the past because the severe temperatures and the oxidizing atmosphere to which the thermal elements have been exposed leads to their rapid destruction and seriously disturbs their calibration. In order to alleviate these difficulties this invention utilizes the change in pressure conditions in the blast tube or air supply duct of a stoker due to changes in the condition of the fuel bed, to indicate whether or not the fire has become extinguished.

One object of this invention is to provide a new and improved control system for stokers.

A further object is to provide a new and improved pressure operated outfire control switch for stoker control systems.

A further object is to provide an alarm in connection with a pressure operated out-fire control for indicating that the stoker has been rendered inoperative.

A further object is to provide a new and improved out-fire mechanism which will deenergize the stoker in the event the fire has become extinguished.

Other objects and advantages reside in certain novel features of construction, circuit arrangement, and operation of the various parts and elements which will be hereinafter more fully described in the specification, particularly pointed out in the appended claims and of which a preferred embodiment is illustrated in the accompanying sheet of drawings forming a part thereof:

Fig. 1 shows the component parts and the circuit connections therefore, of a preferred form of the invention;

Fig. 2 shows a modification of the system shown in Fig. 1;

Fig. 3 illustrates a modification of the pressure switch of Fig. 1 shown in the normal running position.

The preferred circuit shown in Fig. 1 shows two line voltage conductors 6 and 8 connected to a source of power. A transformer choke having a line voltage primary winding 10 is connected in series with the winding of a high voltage relay 12, and the series combination is connected across the two line voltage conductors 6 and 8. The choke is provided with a secondary low voltage winding 14. In the choke secondary circuit there is a room thermostat 16 and an interval timer switch 18 connected in parallel therewith. A safety or lockout switch is provided in the choke secondary circuit and is connected in series with the thermostat 16 and the interval timer switch 18. This safety switch has a plurality of elements including a bimetal actuator member 20 mounted at one end to a support 21 and a bimetal compensator member or blade 22 arranged parallel to the actuator and mounted at one end to the support 23. Cooperating with the actuator 20 and the compensator 22 is a manually reset latch 24 for controlling the circuit through the safety switch. So long as the distance between the movable ends of the two bimetal members 20 and 22 remains less than a predetermined amount, a circuit connection is maintained through the switch 24 by means of the latch 24, but if the distance between the two members 20 and 22 exceeds this predetermined amount, the latch 24 trips downward and opens the circuit through the safety switch. The compensator blade 22 cooperates with the actuator blade 20 to compensate the blade 20 for changes in ambient temperature in order that the latch 24 will release with a predetermined amount of travel of the blade 20 regardless of ambient temperature. A motivating electric heater 26 for the bimetal actuator member 20 is connected in the choke secondary circuit in series with the safety switch. This switch may take the general form of several which are commercially available. For more detailed structural information pertaining to the preferred form reference may be made to Patent No. 2,216,748 issued to Herbert E. Lindemann, on October 8, 1940. While in the preferred form the safety switch operation is obtained by heating a bimetal blade, it is to be understood that any other means of operating the switch may be employed without departing from the spirit of the invention.

A blower 28 is provided as part of the stoker mechanism for feeding air to a combustion chamber 30. An air duct 32 serves to convey the air

under pressure from the blower to tuyères in a retort which serves as the bottom portion of the combustion chamber. A pressure responsive switch such as that shown at A is inserted into the air duct 32 and is electrically wired in parallel with the motivating heater 26.

The pressure switch A consists of a housing 38 supported on the air duct 32. The housing 38 is arranged to have one of its ends open to the duct 32. A flexible diaphragm 40 is clamped to the other end of the housing 38 so as to completely cover it. By this arrangement a change of air pressure in the air duct 32 relative to the atmospheric pressure causes the diaphragm 40 to deflect up or down. Fastened to the diaphragm at 10 its center is an actuator member 42 having an adjustable cap 44 at its end. Fastened to the housing 38 is a spring blade support 46 carrying two spring blades 48 and 50 and a terminal blade 52. These blades are insulated from each other and the support 46 and are so arranged that the adjustable cap 44 on the actuator member 42 will just touch the first spring blade 50 at the selected minimum operating pressure and that the first spring blade 50 will be raised just out of contact with the second spring blade 48 by the actuator member 42 at the selected maximum operating pressure.

With the pressure switch wired as shown in Fig. 1, if the air pressure in the air duct 32 is below the minimum operating value of the pressure switch the actuating member cap 44 will not be in contact with the first spring blade 50 and the normal operating circuit through the pressure switch extending from conductor 54 to conductor 56 will be open. If the minimum pressure is reached, however, a circuit is established through the switch extending from conductor 54, through a conductor 55, through the actuator member 42, through the cap 44, through a portion of the first spring blade 50, through the second spring blade 48, to conductor 56. If the maximum operating pressure is reached the above circuit through the pressure switch is opened by the actuator 42 when the first spring blade 50 and the second spring blade 48 break electrical contact.

Fig. 3 shows a modification of a portion of the pressure switch. It illustrates a method of adjusting the switch to open the electrical circuit through it at selected values of maximum operating pressures. By turning an adjusting screw 58 the compressive force of a spring 60 against the first spring blade 50 is changed and hence the amount of effort required by the actuator 42 to deflect the first spring blade 50 a sufficient amount to open the electrical contact between it and second spring blade 48 is likewise changed. In turn the air pressure required on the diaphragm 40 to cause this contact action must change in order to meet the new restraining force conditions on the first spring blade. Fig. 3 shows the pressure switch in its normal running position.

A pair of relay operated contacts 62 connect and disconnect a stoker motor 64 to the line conductors 6 and 8. An alarm switch 66 is operated responsive to the safety switch latch 24 position by means such as the insulated connecting member 68. An alarm indicator such as the bell 76 is energized from the source of power by means of conductors connected to the line conductors 6 and 8 and through the alarm switch 66 when it is in its closed position.

When the blower 28 is operating, the pressure in the air duct 32 is dependent upon the restric-

tion to the air stream in the combustion chamber 30. If the combustion chamber is practically empty of fuel the static pressure in the air duct 32 will be low. If on the other hand, the combustion chamber is congested and partially full of dense material so that little air can escape from it, the static pressure in the air duct 32 will be high. If the fire in the combustion chamber is burning properly the burning fuel will be fairly porous and will offer only moderate resistance to the passage of fluid through the fuel bed, and as a result there will be only a moderate pressure in the air duct 32. If on the other hand green fuel is being fed into the combustion chamber faster than the fire can consume it, the chamber will become congested with green fuel, the resistance to the air flow through the fuel bed will increase, and as a result the pressure in the air duct 32 will also increase. If the pressure switch A is adjusted to operate at some pressure below the maximum pressure that the blower can produce with a heavily congested combustion chamber, the pressure switch will open its contacts only when the air duct pressure increases sufficiently to indicate a congested condition in the chamber. Obviously, the pressure switch may be adjusted to operate on any desired degree of congestion.

Operation

When the thermostat 16 closes its contacts in response to a change in the temperature of the space being controlled, a closed circuit is established extending from one side of the choke secondary 14 through the thermostat 16, the electric heater 26, and the safety switch 20-24-22 to the other side of the choke secondary. The low impedance connected to the choke secondary reflects itself in the choke primary impedance and causes a reduction in its value. This action reduces the impedance of the relay 12 circuit and causes sufficient current to flow through the relay 12 to fully energize it and cause it to operate. In response the relay contacts 62 close and energize the stoker motor 64. In a conventional installation this starts the fuel feeding means and the air blower 28. If the fuel in the combustion chamber is burning in a normal manner, the restriction to the air passing through the fuel bed will be nominal as will also be the static pressure in the air duct 32. The pressure will be sufficient to exceed the minimum operating pressure of the pressure switch however, and a circuit will be established from conductor 54 to conductor 56 through the path 54-55-42-44-50-48-56 as has been pointed out. In this way the heater 26 will be shunted and made ineffective. If the fuel being fed into the combustion chamber is consumed at a normal rate the pressure of the air in the air duct 32 will remain above the minimum operating pressure setting but below the maximum operating pressure setting of the pressure switch and the stoker will continue to operate until the space being heated has reached a high enough temperature for the thermostat 16 to open its contacts.

However, if the fuel being fed into the combustion chamber 30 is not consumed at a great enough rate, green coal will accumulate in the chamber and the pressure in the air duct 32 will rise to an abnormal value as pointed out. When sufficient congestion has occurred the pressure in the duct 32 will exceed the maximum operating pressure setting of the pressure switch, and the pressure switch will open contacts 48 and 50 and thereby remove the shunt on the actuator

motivating heater 26. In response to the energized heater the bimetal actuator 20 will slowly travel to the left until such time that the pressure switch again closes, or, if this fails to happen, until the latch 24 is released. The latch may be set to release within any practical time limit, 5 minutes for example, after the pressure switch has opened and remains open. When the safety switch opens, the choke secondary circuit is opened and high impedance is reflected in the choke primary causing the relay 12 to open the contacts 62 and shut down the stoker.

It should be noted that the pressure switch may open at intervals for short periods of time without shutting down the system, but intermittent operation of the pressure switch occurring at short durations of time will result in a shut down of the system if the bimetal actuator 20 ultimately reaches the necessary temperature above the temperature of the compensator 22 to release the latch 24.

It should be further noted that any condition in the combustion chamber 30 which will offer abnormal restriction to the flow of air through the fuel bed will cause the system to be shut down. For example, the formation of undesirable fuel slag running down into the tuyères of the retort and clogging them would shut down the system. If the circuit of Fig. 1 is used, the heater 26 is checked for an open circuit condition upon each operation of the system. As explained when the system is shut down there is an open circuit between conductors 54 and 56. Now if the heater is also open because it has been damaged, the choke secondary circuit cannot be completed and hence the relay will not operate.

When the latch 24 trips and drops by gravity or a spring the contacts 66 are closed by the insulating connector 68 and the alarm indicator or signal 70 is energized.

After the latch 24 has been released by the actuator member 20 the system cannot be restarted unless it is manually reset. After the actuator 20 cools, the latch 24 is reset and the alarm circuit is deenergized by raising the movable portion of the alarm switch 66 by means of the insulating lug 71.

The interval timer switch 18 is wired into the system in the conventional manner and serves to start the stoker at regular intervals through its contacts independent of the thermostat 16 in order to "hold" the fire in the combustion chamber. The motor for operating the interval timer switch is continually energized from the source of power associated with the line conductors 6 and 8.

While the "hold-fire" control shown in the Figs. 1 and 2 is of the interval timer type, those skilled in the art will recognize that any other type of "hold-fire" control might be used with the system. The usual limit control 15 is used in the conventional manner to shut down the system in the event of excessive temperature or pressure of the medium being heated by the stoker.

Fig. 2 illustrates a modification of the invention employing a line voltage system. The safety switch in this case is somewhat different from that shown in Fig. 1. Both of the bimetal blades 22 and 20 are provided with an electric heater shown as heaters 72 and 74 respectively. The latch member 76 is arranged to shut down or lock out the system by opening the circuit through the switch when the distance between the free ends of the two bimetal safety switch blades 20

and 22 exceeds or falls short of a certain predetermined amount.

The bimetal blade 20 is slotted at 80 to receive a projecting lug 86 on the latch 76. The lug 86 is arranged to slide within the slot 80 with a predetermined amount of travel of the latch 76 relative to the bimetal blade 20. If the travel of the latch exceeds the predetermined amount, the lug 86 falls out of the slot 80 and causes the latch 76 to drop. For additional information relative to safety switches of this general type, reference may be made to my Patent No. 2,254,984, dated Sept. 2, 1941.

The safety switch heater 12 for the bimetal blade 22 is connected in parallel with the stoker motor 64. The other safety switch heater 74 for the other bimetal blade 20 is normally connected in parallel with the first heater 72 by the normally closed contacts 48-50 of the pressure switch A. A running circuit for the stoker motor extends from the line conductor 6 through either or both the interval timer contacts 18 and the thermostat 16, through the first bimetal blade 20, through the safety switch latch 76, through the second bimetal blade 22, through the stoker motor 64 to the line conductor 8. The motor for the interval timer 18 is energized directly from the line conductors 6 and 8. The alarm signal 70 is energized from the line conductors 6 and 8 through the alarm switch 66.

When the stoker motor 64 is energized the first heater 72 is also energized and causes its associated bimetal blade 22 to slowly warp toward the left. If the pressure switch A is closed the second heater 74 will also be energized and it will cause its associated bimetal blade 20 to slowly warp toward the left along with the bimetal blade 22, and the relative distance between the two bimetal blades will remain approximately the same and the latch 76 will consequently remain engaged. The motion of the two blades will continue until they reach their ultimate positions. If the pressure switch opens, however, at any time, the first bimetal blade 20 will be cooled. As a result the relative distance between the two blades will become smaller and finally the tip of the first bimetal blade will fall in the slot 80 of the latch 76 and the circuit through the safety switch will open when the latch 76 drops down. The alarm signal 70 will be energized when the contacts 66 close as has been described. Obviously if the second heater 74 becomes disabled for any reason, the switch will lock out in the same manner. However, if the first heater 72 fails, a different action ensues. Under these conditions during a normal operation the second heater 74 will be energized while the first heater 72 is inoperative. As a result the relative distance between the two bimetal blades increases until the latch 76 falls out of the slot 80 in the first bimetal blade 20 and the circuit to the stoker motor is opened.

A strip of insulating material 82 is fastened to the end of the bimetal blade 20 to prevent the latch 76 from getting into such a position under the first bimetal blade 20 that the lug 86 would engage the end of the blade and prevent the latch 76 from sliding up on the blade 20 and falling into the slot 80.

With the modification shown in Fig. 2 the correct operation of the heaters 72 and 74 is checked with every operation of the system regardless of how the pressure switch A is connected into the circuit.

While the disclosure given herein shows a relay controlled by a choke circuit, those skilled in

the art will recognize that other types of relay control circuits may be used without departing from the spirit of the invention. Further it will be recognized that the safety switch illustrated in connection with Fig. 2 might be substituted for the safety switch of Fig. 1 and vice versa with equally satisfactory results. Further it is to be understood that any pressure switch of suitable characteristics may be substituted for the pressure switch A disclosed in the drawing. Since only preferred illustrations of the invention have been disclosed, it is conceivable that other modifications thereof may be readily perceived by those well versed in the art and it is therefore desired that the invention be not limited to the precise structure illustrated and described but only to the extent of the appended claims.

What is claimed is:

1. In a control system for a fuel burner having means for feeding fuel and means for feeding combustion air, the combination of, control means for controlling the fuel feeding means, air pressure actuated means actuated by the air passing to the burner and responsive to abnormal combustion air conditions for actuating said control means in a manner to place said fuel feeding means out of operation, means operative upon placing of the fuel feeding means out of operation to retain the same out of operation irrespective of the combustion air conditions, and resetting means for replacing said fuel feeding means into operation.

2. In a control system for a fuel burner having means for feeding fuel and means for feeding combustion air, the combination of, control means for controlling the fuel feeding means, air pressure actuated means actuated by the air passing to the burner and responsive to abnormal combustion air conditions for actuating said control means in a manner to place said fuel feeding means out of operation, means normally retaining the fuel feeding means out of operation when placed out of operation by said pressure actuated means, and manual reset means for actuating said control means in the opposite direction for replacing the fuel feeding means into operation.

3. In a control system for a fuel burner having means for feeding fuel and means for feeding combustion air, the combination of, control means for controlling the means for feeding air, air pressure actuated means actuated by the air passing to the burner and responsive to abnormal combustion air conditions for actuating said control means in a manner to place said means for feeding air out of operation, means normally retaining the means for feeding air out of operation when placed out of operation by said pressure actuated means, and resetting means for replacing said means for feeding air into operation irrespective of such combustion air conditions.

4. In a control system for a fuel burner having means for feeding fuel and means for feeding combustion air, the combination of, control means for controlling the means for feeding air, air pressure actuated means actuated by the air passing to the burner and responsive to abnormal combustion air conditions for actuating said control means in a manner to place said means for feeding air out of operation, means normally retaining said means for feeding air out of operation when placed out of operation by said pressure actuated means, and manual reset means for actuating said control means in the opposite di-

rection for replacing the means for feeding air into operation.

5. In a control system for a fuel burner having means for feeding fuel and means for feeding combustion air, the combination of, control means for controlling the means for feeding air, and means including air pressure actuated means actuated by the air passing to the burner for placing said means for feeding air out of operation in response to abnormal combustion air conditions and for then maintaining the air feeding means out of operation irrespective of the combustion air condition.

6. In a control system for a fuel burner having means for feeding fuel and means for feeding combustion air, both driven by a single motor, the combination of, switching means for controlling said motor, and air pressure actuated means actuated by the air passing to the burner and responsive to abnormal combustion air conditions for actuating said switching means in a manner to place the motor out of operation in response to an abnormal combustion air condition.

7. In a control system for a fuel burner having means for feeding fuel and means for feeding combustion air, both driven by a single motor, the combination of, switching means for controlling said motor, air pressure actuated means actuated by the air passing to the burner and responsive to abnormal combustion air conditions for actuating said switching means in a manner to place the motor out of operation in response to an abnormal combustion air condition, means normally retaining the motor out of operation when placed out of operation by said pressure actuated means, and manual reset means for replacing said motor into operation.

8. In a control system for a fuel burner having air feeding means and fuel feeding means, the combination of, control means for controlling the air feeding means, pressure actuated means for actuating said control means in a manner to place said air feeding means out of operation upon rise or fall in combustion air pressure above or below normal values, means normally retaining the air feeding means out of operation when placed out of operation by said pressure actuated means, and resetting means for actuating said control means to replace the air feeding means into operation.

9. In a control system for a fuel burner having air feeding means and fuel feeding means, the combination of, control means for controlling the fuel feeding means, and pressure actuated means for actuating said control means in a manner to place the fuel feeding means out of operation upon rise or fall in combustion air pressure above or below normal values.

10. In a control system for a fuel burner having means for feeding fuel and means for feeding combustion air, both driven by a single motor, the combination of, switching means for controlling said motor, pressure actuated means for actuating said switching means in a manner to place the motor out of operation upon rise or fall in combustion air pressure above or below normal values, and reset means for replacing the motor into operation.

11. In a control system for a stoker having means for retaining a bed of fuel, fuel feeding means and combustion air feeding means, the combination of, control means for controlling the fuel feeding means, means responsive to the resistance of the fuel bed to passage of combustion air for actuating said control means in

a manner to place the fuel feeding means out of operation when the fuel bed resistance varies to a predetermined value, and means including reset means for at least temporarily placing the fuel feeding means into operation irrespective of the resistance of the fuel bed.

12. In a control system for a stoker mechanism having means for retaining a bed of fuel, a fuel feeding portion and an air feeding portion, the combination of control means for placing at least one portion of the stoker mechanism out of operation, and means responsive to the resistance to flow of combustion air through the fuel bed for actuating said control means for placing said one portion out of operation when the fuel bed resistance rises above or falls below normal values.

13. In a control system for a stoker mechanism having means for retaining a bed of fuel, air feeding means and fuel feeding means, the combination of a control device responsive to the demand for operation and non-operation of the stoker mechanism for placing said mechanism into and out of operation, and control means for the air feeding means, said control means comprising a means responsive to the resistance to air flow through the fuel bed for reducing the air flow upon fall in resistance of the fuel bed, said control means also comprising a time delay device controlled by said control device for rendering the control means ineffective to control the feeding of air until a timed period after the stoker mechanism is placed into operation by said control device.

14. In a control system for a stoker mechanism having means for retaining a bed of fuel, a fuel feeding portion and an air feeding portion, the combination of control means for placing at least the fuel feeding portion out of operation, means influenced by the thickness of the fuel bed for actuating said control means to place said portion out of operation when the thickness of the fuel bed increases to a point indicating that the fire is probably out, and reset means for replacing the fuel feeding portion into operation at least temporarily irrespective of the thickness of the fuel bed.

15. In a control system for a stoker mechanism having means for retaining a bed of fuel, a fuel feeding means and an air feeding means, said air feeding means and said fuel feeding means being driven by a single motor, the combination of switching mechanism for placing said motor out of operation, and means influenced by the thickness of the fuel bed for actuating said switching mechanism to place said motor out of operation when the thickness of the fuel bed increases to a point indicating that the fire is probably out.

16. In a control system for a stoker mechanism having means for retaining a bed of fuel, a fuel feeding means and an air feeding means, said air feeding means and said fuel feeding means being driven by a single motor, the combination of switching mechanism for placing said motor out of operation, means influenced by the thickness of the fuel bed for actuating said switching mechanism to place said motor out of operation when the thickness of the fuel bed increases to a point indicating that the fire is probably out, lock-out means for maintaining the motor out of operation when placed out of operation by said switching mechanism, and reset means for said lockout means for replacing said motor into operation.

17. In a control system for a stoker mechanism having means for retaining a bed of fuel, a fuel feeding means and an air feeding means, said air feeding means and said fuel feeding means driven by a single motor, the combination of a control device responsive to the demand for operation and non-operation of said stoker mechanism for placing said motor into and out of operation, a switching mechanism for placing said motor out of operation irrespective of said control device, and means influenced by the thickness of the fuel bed for actuating said switching mechanism to place the motor out of operation when the thickness of the fuel bed increases to a point indicating that the fire is probably out.

18. In a control system for a stoker mechanism having means for retaining a bed of fuel, a fuel feeding portion and an air feeding portion, the combination of control means for placing the air feeding portion out of operation, and means influenced by the thickness of the fuel bed for actuating said control means to place the air feeding portion of the stoker mechanism out of operation when the fuel bed becomes too thin.

19. In a control system for a stoker mechanism having means for retaining a bed of fuel, a fuel feeding portion and an air feeding portion, the combination of control means for placing said stoker mechanism out of operation, and means influenced by the thickness of the fuel bed for actuating said control means for placing the stoker mechanism out of operation when the fuel bed becomes either too thick or too thin.

20. In a control system for a stoker mechanism having means for retaining a bed of fuel, a fuel feeding portion and an air feeding portion, the combination of a first responsive device responsive to the demand for operation and non-operation of the stoker mechanism for placing said mechanism into and out of operation, a lock-out device for locking at least one portion of the stoker mechanism out of operation, means including a second responsive device arranged to respond generally to the thickness of the fuel bed, and a time delay device controlled by said second responsive device for controlling said lock-out device.

21. In a control system for a stoker mechanism having means for retaining a bed of fuel, a fuel feeding portion and an air feeding portion, the combination of a first responsive device responsive to the demand for operation and non-operation of the stoker mechanism for placing said mechanism into and out of operation, a lock-out device for locking at least one portion of the stoker mechanism out of operation, timing means controlled by said first responsive device for actuating said lock-out device a period of time after the stoker mechanism is placed into operation, and means including a second responsive device arranged to respond generally to the thickness of the fuel bed for arresting action of said timing means if the fuel bed thickness is at a desired value.

22. In a control system for a stoker mechanism having means for retaining a bed of fuel, a fuel feeding portion and an air feeding portion, the combination of a first responsive device responsive to the demand for operation and non-operation of the stoker mechanism for placing said stoker mechanism into and out of operation, a lock-out device for placing at least one portion of the stoker mechanism out of operation, timing means controlled by the first re-

sponsive device for actuating said lock-out device a period of time after the stoker mechanism is placed into operation, and a second device responsive to the pressure of the combustion air fed to the fuel bed for arresting action of the timing means in response to a predetermined change in such pressure following starting of the stoker mechanism.

23. In a control system for a stoker mechanism having means for retaining a bed of fuel, a fuel feeding portion and an air feeding portion, the combination of, a first responsive device responsive to the demand for operation and non-operation of the stoker mechanism for placing said stoker mechanism into and out of operation, a lock-out device for placing at least one portion of the stoker mechanism out of operation, timing means controlled by the first responsive device for actuating said lock-out device a period of time after the stoker mechanism is placed into operation, and a second device responsive to the pressure of the combustion air fed to the fuel bed for arresting action of the timing means when the air pressure is within a predetermined range of values while permitting action of said timing means when the air pressure is above or below said range of values.

24. In a control system for a stoker having means for retaining a bed of fuel, fuel feeding means and combustion air feeding means, the combination of, control means for controlling the fuel feeding means, means responsive to the resistance of the fuel bed to passage of combustion air for actuating said control means in a manner to place the fuel feeding means out of operation when the fuel bed resistance varies to a predetermined value, means normally retaining said fuel feeding means out of operation when said fuel feeding means is placed out of operation by said responsive means, and means including manual reset means for replacing said fuel feeding means into operation.

25. In a control system for a stoker mechanism having means for retaining a bed of fuel, a fuel feeding portion and an air feeding portion, the combination of, a responsive device responsive to the demand for operation and non-operation of the stoker mechanism for placing said stoker mechanism into and out of operation, a control device for placing at least one portion of the stoker mechanism out of operation, timing means adapted when actuated to actuate said control

device a period of time thereafter for placing said one portion of the stoker mechanism out of operation, and means influenced by pressure of the combustion air fed to the fuel bed for arresting the action of said timing means when the fuel bed thickness is satisfactory while actuating said timing means when the fuel bed becomes too thick.

26. In a control system for a stoker mechanism having means for retaining a bed of fuel, a fuel feeding portion and an air feeding portion, the combination of, a responsive device responsive to the demand for operation and non-operation of the stoker mechanism for placing said stoker mechanism into and out of operation, a control device for placing at least one portion of the stoker mechanism out of operation, timing means adapted when actuated to actuate said control device a period of time thereafter for placing said one portion of the stoker mechanism out of operation, and means influenced by the resistance of the fuel bed to flow of combustion air therethrough for arresting the action of said timing means when the fuel bed resistance is satisfactory while actuating said timing means when the resistance of the fuel bed to flow of combustion air becomes improper.

27. In a control system for a stoker mechanism having means for retaining a bed of fuel, a fuel feeding portion and an air feeding portion, the combination of, a responsive device responding to the demand for operation and non-operation of the stoker mechanism for placing the same into and out of operation, a control device for placing at least one portion of the stoker mechanism out of operation, timing means controlled by the responsive device and arranged to be actuated thereby when the stoker mechanism is placed into operation and to be arrested in action when the stoker mechanism is placed out of operation, said timing means adapted when actuated to actuate said control device a predetermined period of time thereafter for placing said one portion of the stoker mechanism out of operation, and means influenced by the resistance of the fuel bed to flow of combustion air therethrough for arresting the action of said timing means when the fuel bed resistance is satisfactory while permitting action of said timing means when the resistance of the fuel bed to flow of combustion air becomes improper.

VIRGIL ROBINS TATE.
